UNITED STATES PATENT OFFICE.

LESTER S. HIRSCH AND HARRY HIRSCH, OF NEW YORK, N. Y.

LIQUID-DISPENSER.

1,296,391.

Specification of Letters Patent. Patented Mar. 4, 1919.

Application filed August 31, 1918. Serial No. 252,192.

To all whom it may concern:

Be it known that we, LESTER S. HIRSCH and HARRY HIRSCH, citizens of Russia, residing at New York, in the county of New York and State of New York, have invented new and useful Improvements in Liquid-Dispensers, of which the following is a specification.

This invention is in the nature of a cap or closure for liquid containers, such as ordinary bottles.

In carrying out the invention it is our purpose to produce a bottle attachment which not only serves as a closure for the neck of the bottle but is provided with means whereby the contents of the bottle may be ejected in desired quantities therefrom.

A further object of the invention is to produce a bottle attachment including a hollow member carrying a tube that is adapted to be inserted in the bottle through the neck thereof, the said member having means whereby to engage with the neck of the bottle and having arranged therein a compressible element designed to be acted upon by a plunger whereby air will be forced into the bottle creating pressure upon the surface of the liquid therein, causing the same to rise through the tube and flow through an outlet spout associated with the tube.

The invention includes the novel features of construction, combination and arrangement of parts hereinafter described and particularly defined in the appended claims.

The drawings illustrate a satisfactory embodiment of the improvement as it now appears to us, but the nature of the invention renders the same susceptible to changes in the details of construction, all of such changes falling within the scope of the claims.

In the drawings:

Figure 1 is a perspective view illustrating the application of the improvement;

Fig. 2 is a vertical longitudinal sectional view through the same;

Fig. 3 is a sectional view illustrating a slight modification.

The bottle 5 illustrated in Figs. 1 to 3 of the drawings is provided with a tapered neck 6 that is engaged by the neck portion 7 of a compressible bulb 8. The bulb 8 at the juncture of the neck 7 therewith is provided with an opening surrounded by an outstanding annular flanged portion 9,

the said flange gripping the spout portion 10 of a tube 11, the said tube being designed to enter the bottle and have its end immersed in the liquid 12 in the said bottle. 60

The hollow compressible bulb member 8 is inclosed in a spherical metallic casing 13, the said casing having a neck extension 14 receiving the neck extension 7 of the bulb 8, the end of the neck extension 14 being 65 provided with an annular depression 15, upon the inner face thereof receiving therein a bead 16 formed on the end of the neck 7 of the bulb 8.

The metallic casing 13, at a point diametrically opposite the flared neck 14 thereof is provided with an annular opening that is surrounded by an outturned annular flange 17, and through this opening, and guided by the flange 17 is a cylindrical 70 plunger member 18. The plunger is preferably in the nature of a tube having its outer end closed and its inner end offset to provide a flange 19, which bears directly upon the outer surface of the compressible 75 bulb 8. Of course, the plunger need not be round in cross section, and it will be apparent that a pressure upon the outer closed end thereof will force the same inward of the spherical casing 13, which compresses 80 the bulb 8, as illustrated in Fig. 2 of the drawings. The collapsing of the bulb causes the air contained therein to pass into the bottle neck, creating pressure upon the surface of the liquid 12 in the bottle which 85 causes the liquid to rise through the tube 11 and to flow through the spout 10 for the said tube.

If desired the plunger may be provided with graduations so that the inward pressure thereof may be readily determined and consequently the quantity of liquid ejected from the bottle may be thus readily regulated. The device is particularly adaptable for employment in connection with bottles 90 retained upon a counter as a desired quantity of liquid may be drawn or ejected therethrough without necessitating the handling or uncorking of the bottle.

In Fig. 3 of the drawings we have illustrated a slight modification, in which a cork member 20 is inserted directly into the mouth 21 of the bottle 22. The cork is provided with an angle passage 23 in the straight portion of which is arranged the 105 upper end of a tube 24, and in the angle portion of which is arranged a discharge 110

spout 25. In addition to the angle passage 23 the cork or stopper 20 is provided with a straight air passage 26. The cork has its outer end formed with a continuous depression 27 receiving therein a bead 28 formed at the juncture of a neck 28' with a metallic approximately spherical casing 29. The neck 28' surrounds the neck 21 of the bottle 22, the outer end of the bottle neck resting upon a shoulder 20' formed between the outer widened and inner reduced portion of the stopper 20. Preferably the reduced portion of the stopper is flared so as to tightly and effectively engage with the inner wall of the bottle neck. The casing 29 is formed, upon its inner face with a continuous depression 30 that provides a seat for the outturned and preferably beaded end 31 of a compressible bulb 32. The end of the bulb is secured in the seat in any desired or preferred manner. The casing 29, at a point diametrically opposite the portion thereof I have referred to as the neck has an opening therein surrounded by a continuous 25 outturned flange 33, and in this opening is arranged a plunger 34 that has its inner and closed end flanged as at 35 to contact with the outer surface of the bulb 32.

The operation is similar to that previously described, it being understood that under normal conditions the contents of the bottle will be sealed to the outer air so that the improvement not only provides a means for ejecting the contents from the bottle 35 but also serves as a sealing element for such contents.

Having thus described the invention, what is claimed as new, is:—

1. A bottle attachment for the purpose

described, comprising a hollow metallic casing having a neck portion designed to surround the neck of a bottle, a compressible bulb in said casing, a tube having a spout extending angularly through the casing and said tube designed to be received in the 45 bottle and a plunger movable through the casing and contacting with the bulb.

2. A bottle attachment for the purpose described comprising a hollow metallic casing removably connected to the mouth of a 50 bottle, a tube carried by the casing adapted to enter the bottle through the neck thereof, said tube having an angle portion providing a spout passing through one side of the casing, compressible means for securing the 55 tube to the casing, a diaphragm in the casing, and a plunger movable through the casing for operating said diaphragm.

3. A bottle attachment for the purpose described, comprising a hollow metallic casing having a neck portion designed to surround the neck of a bottle, a compressible bulb in the casing having a neck extension received in the neck of the casing and contacting with the neck of the bottle, said bulb having an opening therein, a flange surrounding said opening and passing through an opening in the side of the casing, a tube having an angle spout portion passing through said flange, and a plunger movable 70 through the outer end of the casing and having an inner flanged portion contacting with the bulb.

In testimony whereof we affix our signatures.

LESTER S. HIRSCH.
HARRY HIRSCH.
